CLAIM

The ornamental design for a vegetation blade, as shown and described.

DESCRIPTION

FIG. 1 is a bottom perspective view of the vegetation blade.

FIG. 2 is a top perspective view of the vegetation blade.

FIG. 3 is front view of the vegetation blade.

FIG. 4 is a side view of the vegetation blade.

FIG. 5 is a bottom view of the vegetation blade; and,

FIG. 6 is a cross sectional view of the vegetation blade taken along line 6—6.

The broken line showing of two segments of flexible cutting material is included for the purpose of illustrating location of said segments, which are required for the vegetation blade to function.

Vegetation blade is a one-piece article in the general shape of a disc. Two segments of flexible cutting material must be attached thereto and are required for the vegetation blade to cut vegetation. It is a lawnmover blade used to cut vegetation. It is a replacement blade for any conventional lawnmower blade because it is reversibly attachable to any conventional lawnmower, including those that use multiple blades.
